Primary Examiner — Karen E. Eldridge Powers
Assistant Examiner — Jasmine Mlinarcik

CLAIM

(57) I claim the ornamental design for a necktie with a reversed pattern section, as shown and described.

DESCRIPTION

FIG. 1 is a front elevation view of the necktie with a reversed pattern section.

FIG. 2 is a back elevation view of the claimed design.

FIG. 3 is a left side elevation view of the claimed design.

FIG. 4 is a right side elevation view of the claimed design.

FIG. 5 is a top plan view of the claimed design; and,

FIG. 6 is a bottom plan view of the claimed design.

The solid black shading shown in the drawings illustrates a contrast in color.
